B. P. Coston,

Washing Machine.

Patented Apr 27 1832.

Apr 27, 1832

Bentlow & Boston of the City of Philadelphia Pennsylvania

The Schedule referred to in these Letters Patent and making part of the same, containing a description in the words of the said Bentlow & Boston himself of his Improvement in the Machine for Washing Clothes.

Be it known that J. Bentlow & Boston of the City, County of Philadelphia, and State of Pennsylvania, have made an improvement in the Machine for Washing Clothes, which is described as follows. A box (a box of any convenient size & dimensions, water tight, and placed on four legs, of a convenient height; this box is to contain the water, clothes, fluted washboard, and fluted roller. Two bars are placed one on each side of the Machine near the bottom. The fluted wash board, is about two thirds of the length and one half, the width of the length, made of hard wood of a curved, notched shape, the ribs or plates, are about 5. eighths of an inch apart. A swinging frame with a cylindrical ribbed or fluted roller, is made to work on the ribbed or fluted wash board. The frame consists of two arms about 39 feet long, extending over the sides of the machine, having a top rail equal to the whole width of the machine. Two hanging arms, about 12 inches long, are suspended from this head or top rail, for receiving the fluted cylinder. Spring to be next described. The swinging frame turns on pins or screws, fixed in the lower bars before mentioned. The fluted roller is made of a length equal to the width of the wash board. A coiled spiral, or other spring is placed over two rods which are put in cylindrical openings through each of the hanging arms; and the fluted roller turns on pins passing through eyes in the lower ends of these rods. A screw is placed over the spring in the head of the frame, for regulating the pressure on them. Slots are left in the hanging arms at top & bottom for allowing the spring to act, and the fluted roller to rise and fall. The hanging arms are united together by a round

cross bar which serves as a handle. A loose cover is put over the whole box. .... Operation. .... The water, clothes, and soap, being put into the box, the clothes after being soaped & wrung, are put upon the ribbed or fluted board. the swinging frame with the ribbed or fluted roller is brought up (to) wash board, this pushes the water forward and forces it through the clothes, thus washing or extracting the dirt out of them. .... When the clothes are washed the water is drawn off by a plug at the bottom of the box. This machine may be used for washing wool, straw, and bristles, or any other soft pliable substance.

The invention here claimed & desired to be secured by Letters Patent, is the before described machine for washing clothes, wool, straw, bristles or any other soft pliable substance requiring care, particularly the manner of suspending the fluted roller, & regulating the same by the rods in the hanging arms, spiral spring and regulating screw, so as to give any degree of pressure on the substance to be washed which may be required. For a further illustration of my invention refer to the model and drawing of the same deposited in the Patent office.

In testimony whereof, I have caused to be subscribed my name at the City of Washington this 16th day of April 1832.
